UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed July 20, 1929. Serial No. 379,692.

My invention relates to a slicing machine of the type wherein a circular knife is employed, herein shown as motor driven. One object of the invention is the provision of means for protecting the fingers of the operator from the knife. Another object is the provision of means for completely enclosing or shielding the cutting edge from the rear or slice discharge side. Another object is the provision of means for shielding the cutting edge of the knife from the rear or slice discharge side at all normal positions of the gauge plate. Another object is the complete protection or shielding of the exposed periphery of the knife.

Other objects will appear from time to time in the course of the specification and claims.

I illustrate my invention more or less diagrammatically in the accompanying drawings, wherein—

Figure 1 is a plan view, with parts in section;

Figure 2 is a rear elevation;

Figure 3 is a partial front elevation;

Figure 4 is a section on the line 4—4 of Figure 3; and

Figure 5 is a section on the line 5—5 of Figure 3 with parts omitted.

Like parts are indicated by like symbols throughout the specification and drawings.

Referring to the drawings, A generally indicates the base or support of a slicing machine, which may be provided with the

ground engaging studs or pads A¹. Any suitable motor means may be provided

housed for example at B. B¹ diagrammatically illustrates the end of the motor shaft,

B² a pulley thereon and B³ a belt driven by said pulley.

C generally indicates a rotary knife which may be shown as somewhat cupped forwardly as at C¹ and provided with the front and rear recesses C² and C³ respectively, adjacent the periphery of the knife. C⁴ indicates any

suitable knife shaft with which is associated the pulley C⁶ about which passes the belt B³. C⁶ generally indicates any suitable bearing portion or sleeve which may be associated with or mounted upon the frame or base

A. Associated with it is the frame portion

C⁷ which extends forwardly toward the knife and conforms generally to the rear recess C³ of the knife, as shown for example in Figure 1.

Positioned forwardly in front of the knife and mounted in any suitable manner on the base or frame is the guard plate D which is shown as centrally somewhat forwardly bowed as at D¹. It may be mounted upon the upward projection D² of the frame. D³ indicates a cover portion overlying the frame portion D² and overlying and enclosing the upper edge of the plate D. It will be seen, for example in Figures 2 and 3, that the cover portion D³ extends outwardly over the knife and masks the upper portion of the periphery of the knife shown in dotted line as at D⁵. As shown in Figure 1, the axis of the knife is somewhat tilted from perpendicularity to the guard plate D and the arcuate portion D⁶ of the guard plate is thereby permitted to penetrate the forward recess C² of the knife, as shown in Figures 1 and 3.

E¹ indicate tracks upon which any suitable work support, generally indicated as E² may reciprocate. The work support is provided with a pusher plate generally indicated as E³ which may be guided for example by the sleeve E⁴ upon the handle pin E⁵. It will be seen that the forward edge 75 of the carrier E² terminates somewhat short 70 of the cutting plane, as at E⁶ and is corrugated or indented as at E⁷.

G generally indicates a gauge plate the arcuate edge G¹ of which conforms generally 85 to the arc of the knife, as shown for example in Figure 3. The gauge plate G may be mounted in any suitable manner upon the supporting structure G² which may be moved toward and away from the cutting plane, as 90 by rotation of the manual control knob G³. The particular actuating connection between the knob and the gauge plate support is not shown in detail, since its details do not form part of the present invention. G⁴ generally 95 indicates a guard to the rear face of the knife. Under some circumstances it may be desired to form it integrally with the gauge plate but I herein illustrate it as attached thereto as 100 for example by the screws G⁵. The details

of the securing arrangement are shown for example in Figure 5. A plane portion G^6 of the guard G^4 is interposed between the gauge plate proper, G , and the supporting structure G^2 . The securing screw G^5 , with its screwthreaded aperture G^7 , is in screwthreaded engagement with the screw stem G^8 , rearwardly projecting from the gauge plate G . It will be understood that any desired number of such securing screws may be employed but in Figures 2 and 3 I illustrate, so far as concerns the attachment of the guard G^4 , two. The portion G^6 of the guard is provided with an aperture G^9 of such size as to permit substantial adjustment of the support in relation to the gauge plate or the gauge plate support. It will be observed that the guard G^4 is arcuate in form and extends laterally toward the center of the knife from the edge of the gauge plate and overlaps the rear face of the knife. It will be understood that this overlap is preferably sufficiently great to cause the member G^4 to mask the cutting edge of the knife from the rear at all normal positions of the gauge plate. In other words, in the preferred form of my device, no matter how far the gauge plate may be withdrawn rearwardly from the cutting plane, the guard G^4 overlaps the cutting edge and the rear of the knife sufficiently to make it difficult or impossible for the operator to insert his finger, from the rear, into damaging contact with the cutting edge of the knife.

H generally indicates a work and slice supporting member, which may be mounted on the frame and extends beneath the lower edge of the gauge plate G . Preferably it lies in part on both sides of the cutting plane, in close contact with the forward edge E^6 of the work support E^2 . It extends also to the rear of the knife, as at H^1 , it being understood that the portion opposed to the knife conforms closely to the contour of the rear of the knife. The member H may be adjusted, as by the securing screw H^2 which passes through an aperture H^3 of sufficient size to permit both transverse and longitudinal adjustment. When the screw H^2 is drawn up movement of the bar H is prevented.

I generally indicates a slice receiving tray or container which may be removably mounted upon the base A . It may be provided with a handle portion I^1 , whereby it may be lifted or withdrawn from operative position. It is provided at its inner end with the terminal flange I^2 which masks the lower portion of the periphery of the knife as shown at I^3 in Figure 2. The upper edge of the flange I^2 conforms closely to the lower face or edge of the member H .

It will be realized that whereas I have described and shown a practical and operative device, nevertheless many changes might be

made in the size, shape, number and disposition of parts without departing from the spirit of my invention. I therefore wish my description and drawings to be taken as in a broad sense illustrative.

The use and operation of my invention are as follows:

In a slicing machine of the type herein disclosed in which a motor driven knife is employed, it becomes extremely important to mask or guard the cutting edge of the knife. The importance of such masking will be realized when it is considered that the peripheral speed of the knife is enormous. In one form of my device a knife having a diameter of eight inches is rotated at a rate of 1750 R. P. M. The slightest contact of the hand of an operator to the cutting edge may result in an instant and serious wound. Hence the importance of making it as impossible or practically impossible for the operator to bring his hand into unintended contact with the knife. Of almost equal importance is the necessity of preventing access to the cutting edge of the knife of hard substances which would damage the delicately ground very thin cutting edge.

Considering particularly masking the cutting edge of the knife from the rear I have so disposed the parts of the present device as to make it practically impossible for the operator to have any unintended access to the cutting edge. The cover D^8 masks the upper edge of the periphery of the knife, as shown at D^5 , so far as the periphery of the knife extends outwardly from the frame. The flange I^2 of the tray I masks the lower edge of the knife as at I^3 . The inner extension H^1 of the bar or work or slice support H masks the cutting edge of the knife between the bottom of the gauge plate G and the top of the flange I^2 of the tray. It is necessary for the operation of the device that the gauge plate be movable rearwardly away from the cutting plane. This is necessary to provide a throat of sufficient width to pass slices of the maximum thickness to be sliced. In order to prevent access to the cutting edge so exposed I provide the supplemental guard G^4 which overlaps the edge and rear face of the knife, and which extends inwardly toward the center of the knife a sufficient distance to make it difficult or impossible for the operator even voluntarily to insert a finger between the edge of the gauge plate and the cutting arc of the knife. I find it desirable to permit a certain measure of adjustment of the bar H , as by the screw H^2 . I also find it desirable to provide an adjustment of the guard G^4 in relation either to the gauge plate G or the gauge plate support G^1 or both. This adjustment is effected by releasing the screw G^5 to permit the member G^4 to be moved, the aperture G^9 therein being

of sufficient size to permit a substantial measure of adjustment.

I claim:

- 5 1. In a slicing machine having a rotary knife and means for rotating it, a carriage and means for guiding it across the plane of the knife, a gauge plate lying in a plane generally parallel with the path of movement of said carriage and means for moving it toward and away from said carriage, a slice receiving tray positioned to the rear of said knife, and a work supporting member extending along the path of movement of said carriage and provided with a portion closely adjacent and conforming to the contour of the rear face of the periphery of the knife, said slice receiving tray including a flange upwardly extending and adapted to mask a portion of the arc of the knife below its cutting arc, said work supporting member protecting the arc of said knife between the cutting arc and the top of the said flange.
- 10
- 15
- 20

2. In a slicing machine having a rotary
25 knife and means for rotating it, a carriage
and means for guiding it across the plane
of the knife, a gauge plate lying in a plane
generally parallel with the path of move-
ment of said carriage and means for moving
it toward and away from said carriage, a slice
30 receiving tray positioned to the rear of said
knife, and a work supporting member ex-
tending along the path of movement of said
carriage and provided with a portion closely
adjacent and conforming to the contour of
35 the rear face of the periphery of the knife,
said slice receiving tray including a flange
upwardly extending and adapted to mask a
portion of the arc of the knife below its cut-
ting arc, said work supporting member pro-
40 tecting the arc of said knife between the cut-
ting arc and the top of the said flange, and a
guard associated with said gauge plate, said
guard being inclined rearwardly from said
gauge plate toward the center of rotation of
45 the knife and being adapted to overlie and
mask the rear of the cutting arc, the space
between said guard and the knife being suf-
ficient to permit the movement therethrough
50 of the slices severed from the work by the
knife.

3. In a slicing machine having a rotary knife and means for rotating it, a carriage and means for guiding it across the plane of the knife, a gauge plate lying in a plane generally parallel with the path of movement of said carriage and means for moving it toward and away from said carriage, a slice receiving tray positioned to the rear of said knife, and a work supporting member extending along the path of movement of said carriage and provided with a portion closely adjacent and conforming to the contour of the rear face of the periphery of the knife, said slice receiving tray including a flange upwardly extending and adapted to

mask a portion of the arc of the knife below its cutting arc, said work supporting member protecting the arc of said knife between the cutting arc and the top of the said flange, and a guard associated with said gauge plate, said guard being inclined rearwardly from said gauge plate toward the center of rotation of the knife and being adapted to overlie and mask the rear of the cutting arc, the space between said guard and the knife being sufficient to permit the movement therethrough of the slices severed from the work by the knife, and a cover member overlying the upper portion of the periphery of the knife, said guard protecting the cutting arc of the knife from the lower edge of said cover member to the upper edge of said work supporting member. 70 75 80

4. In a slicing machine which includes a rotary knife and means for rotating it, a carriage and means for guiding it across the face of the knife, a gauge plate generally parallel with the path of movement of the carriage and means for moving it toward and away from the path of movement of the carriage, and a guard member secured in relation to said gauge plate, said guard member being adapted to overlie the rear face of the knife and to shield the cutting arc from the rear, at substantially all positions of the gauge plate, and a slice receiving member positioned to the rear of the knife, said slice receiving member including a portion adapted to mask the cutting edge of the knife below said guard member. 85
90
95
100

5. In a slicing machine which includes a rotary knife and means for rotating it, a carriage and means for guiding it across the face of the knife, a gauge plate generally parallel with the path of movement of the carriage and means for moving it toward and away from the path of movement of the carriage, and a guard member secured in relation to said gauge plate, said guard member being adapted to overlie the rear face of the knife and to shield the cutting arc from the rear, at substantially all positions of the gauge plate, and a slice receiving member positioned to the rear of the knife, said slice receiving member including a portion adapted to mask the cutting edge of the knife below said guard member, and a slice supporting member interposed between the lower edge of the gauge plate and the upper edge of the slice receiving member and adapted to mask the cutting edge of the knife therebetween. 105 110 115 120
